York, N. Y., a corporation of Delaware

Application October 25, 1944, Serial No. 560,216

6 Claims. (Cl. 62—5)

1

The present invention relates to improvements in valves and more particularly to an automatically operable check valve for permitting the flow of fluids in one direction while preventing the flow of fluids in the opposite direction.

While the valve of the present invention may have other uses it is particularly adapted for use in absorption refrigeration systems of the type illustrated and described in the application for United States Letters Patent of Albert R. Thomas, Serial No. 560,214, filed October 25, 1944, now Patent Number 2,518,202, dated August 8, 1950, and entitled "Refrigeration." Systems of this type operate in a partial vacuum and utilize water as a refrigerant and a saline solution as an absorbent. In such refrigeration systems non-condensable gases may accumulate in the various elements thereof which interfere with the proper operation of the system. The non-condensable gases are usually purged from the system periodically by means of a vacuum pump or other suitable exhausting means.

One of the objects of the present invention is to provide a valve of the type indicated between the refrigeration system and exhausting means to permit the flow of non-condensable gases from the system and prevent the flow of atmospheric air into the system.

Another object is to provide a valve of the type indicated which is automatically operable by slight differences in pressure at opposite sides thereof to open or close the same.

Still another object is to provide a valve of the type indicated having a flexible impervious diaphragm extending across the conduit and adapted to cooperate with the end of a by-pass tube connecting the conduit at opposite sides of the diaphragm.

These and other objects will become more apparent from the following description and drawings in which like reference characters denote like parts throughout the several views. It is to be expressly understood, however, that the drawings are for the purpose of illustration only and not a definition of the limits of the invention, reference being had for this purpose to the appended claims. In the drawings:

Fig. 1 is a diagrammatic view of an absorption refrigeration system incorporating the automatically operable check valve of the present invention and showing the relationship of the valve with respect to the other elements of the system, and

Fig. 2 is an enlarged part sectional view of the valve.

2

The automatically operable check valve of the present invention is shown in Fig. 1 as applied to an absorption refrigeration system which operates in a partial vacuum. In such an absorption refrigeration system, liquid refrigerant such as, for example, water is introduced into the evaporator 10 from a condenser 11 through a path of flow including a U-shaped tube 12. The evaporator 10 is in the form of a horizontal cylindrical drum and the U-shaped tube 12 has one end connected to a sump 13 at the bottom of the condenser 11 with its opposite end extending upwardly through the bottom of the evaporator. Refrigerant vapor formed in the evaporator 10 flows to an absorber 14 where it is absorbed into a liquid absorbent such as, for example, a concentrated water solution of lithium chloride, lithium bromide, or the like. The absorber 14 also is in the form of a horizontal cylindrical drum and is positioned directly below the evaporator 10. A pipe 15 extends upwardly from the top of the absorber 14 through the bottom of the evaporator 10 and for a considerable distance above the bottom to provide a stand-pipe in the evaporator. The stand-pipe 15 is adapted to exhaust refrigerant vapor from the evaporator 10 to the absorber 14 while maintaining a body of liquid refrigerant in the evaporator.

The absorption liquid enriched with refrigerant, or, in other words, the dilute salt solution, is conducted from the absorber 14 to the base of a generator 16 in a path of flow including conduit 17, pump 18, conduits 19 and 20, liquid heat exchanger 21, and conduit 22. Within the generator 16 are disposed a plurality of riser tubes 23 enclosed in a chamber formed by an outer shell 24 and to which steam is supplied through a conduit 25 from a suitable source of supply. The flow of steam through the conduit 25 is controlled by a modulating valve 26 operated by a suitable servo-motor 66 responsive to variations in the resistance 62 of an electric circuit 65. Preferably the steam chamber in the generator 16 is provided with an outlet vent 27 adjacent its upper end and a condensate return line 28 adjacent the base thereof. The heating of the riser tubes 23 by the steam causes refrigerant vapor to be expelled from the absorption solution and such expelled vapor is effective to raise the absorption solution by gas or vapor-lift action.

The expelled vapor passes from the upper ends of the riser tubes 23 into the vapor separator 29 and thence flows through a conduit 30 to the

condenser 11 where the vapor is liquefied. Liquid refrigerant formed in condenser 11 flows through the U-shaped tube 12 to the evaporator 10, as explained above, to complete the refrigeration cycle. The raised absorption solution from which refrigerant vapor has been expelled is conducted from the upper part of the generator 16 to the absorber 14 in a path of flow including a conduit 31, chamber 32, conduit 33, liquid heat exchanger 21, and conduit 34. The end of the conduit 34 extends into the absorber 14 in the upper portion thereof adjacent the inlet from the stand-pipe 15 and has a plurality of apertures or nozzles therein to provide a spray pipe 35 for dividing the absorption solution into a spray as it is introduced into the absorber to promote absorption of the refrigerant vapor. The heat liberated by the absorption of the refrigerant vapor in absorber 14 is transferred to a cooling medium such as, for example, water, which flows upwardly through vertically disposed banks of pipes 36 in the absorber. The cooling water is introduced into the lower ends of the banks of pipes 36 from a supply main 37 and is discharged from the upper ends of the banks of pipes through a conduit 38. The conduit 38 is connected to condenser 11 so that the cooling water also may be utilized to effect cooling of the condenser. The cooling water is discharged from the condenser 11 through a conduit 39.

The system operates in a partial vacuum with generator 16 and condenser 11 operating at one pressure and evaporator 10 and absorber 14 operating at a lower pressure. The pressure differential between the high and low pressure sides of the system is maintained by a liquid column in the up-leg of the U-shaped tube 12 between the condenser 11 and evaporator 10; a liquid column in the conduit 34 connecting the absorber 14 and heat exchanger 21; and by the pump 18 connecting the conduits 17 and 20 between the absorber 14 and generator 16.

The liquid refrigerant in the evaporator 10 is circulated continuously in a loop-circuit to adapt the system to refrigerate at a place remote from the evaporator. The loop-circuit comprises a conduit 42, pump 43, conduit 44, cooling element 45 and conduit 46. The conduit 42 has one end extending into a sump 47 at the bottom of the evaporator 10 to receive liquid refrigerant and its opposite end is connected to the inlet port of the pump 43. The conduit 44 is connected between the outlet from the pump 43 to the inlet of the cooling element 45 and the conduit 46 is connected between the outlet from the cooling element to the upper part of the evaporator 10. The cooling element 45 is illustrated diagrammatically as a coil but it will be understood that this element may have other forms such as a radiator, or the like, depending upon the particular installation. As illustrated in Fig. 1 of the drawings the outlet end of the conduit 46 extends into the evaporator 10 and is provided with a series of apertures or nozzles to provide a spray pipe 48 for dividing the liquid refrigerant into a spray as it is returned to the evaporator to promote evaporation. Preferably a baffle plate 49 is provided in the evaporator 10 between the end of the spray pipe 48 and the stand-pipe 15 to prevent the liquid refrigerant from being swept into the stand-pipe with the refrigerant vapor.

The absorption solution in the absorber 14 also is circulated continuously through an auxiliary loop circuit to promote absorption of the re-

frigerant vapor. The auxiliary loop circuit for the absorption solution comprises the conduit 17, pump 18, and conduit 19. One end of the conduit 17 extends into a sump 54 in the bottom of the absorber 14 and the lower end of the conduit is connected to the inlet port of the pump 18. The conduit 19 is connected at one end to the outlet port of the pump 18 and its opposite end 52 extends horizontally into the upper part of the absorber 14 throughout substantially the entire length of the latter. The horizontally extending portion 52 of the conduit 19 is provided with a plurality of spray heads 55 each of which comprises a nozzle and a conical deflecting plate for dividing the absorption solution into a spray and distributing the spray over the banks of cooling pipes 36 to promote absorption of the refrigerant. During operation of the refrigeration system part of the circulating absorption solution is diverted from the conduit 19 through the conduit 20 and heat exchanger 21 to the generator 16 as previously described.

To prevent the progressive concentration of the absorption solution under certain conditions of operation and the crystallization and precipitation of salt resulting from such progressive concentration a control means is provided which is responsive to the concentration of the absorption solution and connected to adjust the valve 26 to regulate the amount of steam supplied to the generator 16. The control means may be located in any part of the refrigeration system where the progressive concentration of the absorption solution is likely to occur. As illustrated in Fig. 1 of the drawings a control float 57 is located in the chamber 32 in the return line between the generator 16 and heat exchanger 21. The float 57 has a specific gravity such as to adapt it to rise when the concentration of the absorption solution has a predetermined value. The concentration control float 57 has an arm 58 extending outwardly from the chamber 32 through a flexible bellows 59 to permit relative movement and the arm is pivoted at 60. The flexible bellows 59 acts as a load spring opposing movement of the float 57 so that arm 58 has a movement proportional to changes in the specific gravity or concentration of the solution.

The outer end of the float arm 58 constitutes a movable contact 61 for varying the resistance 62 of the electric circuit 65 for servo-motor 66. Thus, the servo-motor 66 is operated upon movement of the float 57 to adjust the valve 26 to regulate the flow of steam to the generator 16 in accordance with variations in the concentration of the absorption solution. Preferably a baffle plate 67 is provided in the chamber 32 adjacent the end of the conduit 31 to prevent the velocity of the stream of incoming absorption solution from affecting the operation of the control float 57. The end of the conduit 33 extends upwardly in the chamber 32 above the control float 57 to insure immersion of the float by the absorption solution.

Preferably an overflow by-pass 68 is provided between the separating chamber 29 of the generator 16 and the bottom of the absorber 14. As illustrated in Fig. 1 of the drawings the upper end of the overflow by-pass 68 is protected by a baffle 69 and its opposite end is in the form of a vertical riser 70 to maintain a column of liquid absorbent for balancing the difference in pressure between the generator 16 and absorber 14.

75 A portion of the absorption solution circulat-

ing in the auxiliary loop circuit is utilized to withdraw non-condensable gases from the absorber 14. The absorption solution is diverted from the conduit 19 of the auxiliary loop circuit through a conduit 71 to a Venturi tube 73 which, in turn, is connected to a separating chamber 74 by a conduit 75. A conduit 76 connects the separating chamber 74 to the top of the absorber 14, see Fig. 1. Connected to the Venturi tube 73 adjacent its constricted throat is a conduit 77 having its opposite end extending into the absorber 14 to a position where the non-condensable gases accumulate. Due to the flow of the absorption fluid through the throat of the Venturi tube 73 the area adjacent the throat is evacuated which draws the non-condensable gases through the conduit 77. The non-condensable gases drawn into the Venturi tube 73 are entrained in the absorption solution and carried into the separating chamber 74. As illustrated in the drawings a baffle plate 78 is provided in the separating chamber 74 to prevent the non-condensable gases from entering the conduit 76. Extending upwardly from the top of the separating chamber 74 is a conduit 79 which is connected at its upper end to a float chamber 80. The float chamber 80, in turn, is connected to one side 81 of a valve chamber by means of a connecting conduit 82, see Fig. 2. The opposite side 83 of the valve chamber is connected to a water operated aspirator 84 by means of a conduit 85. Water is supplied to the aspirator 84 from the supply main 37 through the pipe 86 and the water is discharged from the aspirator through a discharge tube 87.

In accordance with the present invention a novel form of automatically operable check valve 88 is provided in the path of flow of the non-condensable gases between the refrigeration system and the aspirator 84 which permits the flow of the gases therethrough while preventing the flow of atmospheric air into the system. The check valve 88 comprises a flexible impervious diaphragm 90 extending across the valve chamber to hermetically seal the side 81 from the side 83 and a by-pass conduit or tube 91 extending from the side 81 of the chamber to the conduit 85. The inner end 92 of the by-pass tube 91 is positioned adjacent the flexible diaphragm 90 and constitutes a valve seat adapted to be engaged by the diaphragm to close the conduit. Preferably a resilient valve plate 93 of a suitable synthetic rubber or the like is mounted on the diaphragm for engagement with the valve seat at the end 92 of the by-pass tube 91.

The flexible diaphragm 90 normally engages the valve plate 93 with the end 92 of the by-pass tube 91 with a slight initial pressure to seal the side 81 of the valve chamber from the atmosphere. The side 83 of the valve chamber is subjected to the pressure in the conduit 85 to maintain the valve plate 93 engaged with the valve seat at the end of the by-pass tube 91. Thus, if the pressure in the conduit 85 and side 83 of the valve chamber is the same or greater than the pressure in the side 81 of the chamber the valve plate 93 is firmly engaged with the end 92 of the by-pass tube 91 to seal the refrigeration system from the atmosphere. However, when the aspirator 84 evacuates the conduit 85 and side 83 of the valve chamber to a pressure below that prevailing in the side 81 of the chamber the diaphragm 90 will be flexed to the dash line position illustrated in Fig. 2 to open the end 92 of the by-pass 91 and permit the non-con-

densible gases to escape therethrough to the conduit 85.

One form of the invention having now been described in detail the mode of operation of the apparatus is explained as follows:

For purposes of illustration let it be assumed that the system is not operating and that the concentration control float 57 is in the position illustrated in Fig. 1 of the drawings. To initiate operation of the refrigeration system steam is supplied through the conduit 25 to the generator 16 and water is supplied from the main 37 to the cooling coils 36 in the absorber 14 and through the conduit 38 to the condenser 11. Simultaneously operation of the pumps 18 and 43 is initiated to circulate refrigerant and absorption solution in their respective loop circuits. With the float 57 in the position illustrated in Fig. 1 the valve 26 will be adjusted to supply steam to the generator 16 for full load conditions. The steam in the generator 16 vaporizes water from the absorption solution standing in the riser tubes 23 and the water vapor will rise in the tubes to the vapor separating chamber 29 and will raise the concentrated absorption solution from which the water has been expelled by vapor-lift action.

The refrigerant vapor will pass through the conduit 30 and the condenser 11 where the vapor will be liquefied by its contact with the relatively cold tubes therein. The liquid refrigerant in the condenser 11 then will flow by gravity into the sump 13 and through the U-shaped tube 12 to the evaporator 10.

The liquid refrigerant delivered to the evaporator 10 will accumulate therein around the stand pipe 15 and will be continuously circulated through the auxiliary loop circuit by the pump 43. The vaporized refrigerant in the evaporator 10 will flow through the stand pipe 15 to the absorber 14 where it will be absorbed in the absorption solution delivered to the absorber from the separating chamber 29 through a path of flow comprising the conduit 31, chamber 32, conduit 33, heat exchanger 21, conduit 34 and spray pipe 35. To promote absorption the absorption solution will be continuously circulated through its auxiliary loop circuit by the pump 18. A portion of the absorption solution circulating in the auxiliary loop circuit will be diverted continuously through the conduit 20, heat exchanger 21 and conduit 22 to the base of the generator 16 to complete the refrigeration cycle. The absorption solution flowing from the absorber 14 is comparatively cool while the concentrated absorption solution flowing from the vapor separator 29 to the absorber 14 is relatively hot. As these two streams of absorption solution pass each other during their flow in separate paths through the heat exchanger 21 the dilute solution flowing to the generator 16 from the absorber 14 will be heated by the concentrated solution flowing to the absorber from the generator.

The float 57 in the chamber 32 moves in response to changes in the specific gravity or concentration of the absorption solution to continually adjust the valve 26 to control the amount of steam flowing to the generator. Thus, if the absorption solution becomes too concentrated, less steam will be supplied to the generator 16 until the concentration becomes more dilute at which time more steam will be supplied to the generator. Thus, the modulating control valve 26 will operate continuously to maintain the proper concentration of absorption solution in the system.

A portion of the absorption solution circulating in the auxiliary loop circuit will be fed continuously through the conduit 71 to the Venturi tube 73. The flow of absorption solution through the constricted throat of the Venturi tube 73 will evacuate the area adjacent the throat and withdraw non-condensable gases from the absorber 14 through the conduit 71. The non-condensable gases drawn into the Venturi tube 73 through the conduit 71 will be entrained in the absorption solution and delivered through the conduit 75 to the separating chamber 74. The absorption solution in the separating chamber 74 will flow through the conduit 76 back to the top of the absorber 14. As the point of connection of the conduit 76 with the separating chamber 74 is positioned above the lower end of the conduit 75 the non-condensable gases will bubble upwardly through the absorption solution which operates to strip any refrigerant therefrom. The non-condensable gases bubbling upwardly through the absorption liquid will accumulate in the riser tube or conduit 79, float chamber 80, conduit 82 and side 81 of the valve chamber and displace any absorption liquid therein.

The non-condensable gases will be withdrawn continuously from the system by the water-operated aspirator 84. Water supplied to the aspirator 84 from the supply main 37 through the conduit 86 and passing through a constricted throat thereof will evacuate the area adjacent the constricted throat including the conduit 85 and side 83 of the valve chamber. When the pressure in the side 83 of the valve chamber is less than the pressure in the side 81 the diaphragm 90 will flex automatically from the full line position to the dash line position illustrated in Fig. 2 to withdraw the valve plate 93 from the end 92 of the by-pass conduit 91 constituting a valve seat. The non-condensable gases in the side 81 of the valve chamber then will flow from the system through the by-pass conduit 91 to the conduit 85 and will be exhausted by the aspirator 84. If for any reason the pressure in the side 83 of the valve chamber increases above the pressure in the side 81 the resultant pressure on the flexible diaphragm 90 will flex it to the full line position illustrated in Fig. 2 to engage the valve plate 93 with the end 92 of the by-pass tube 91 and seal the refrigeration system from the atmosphere. Preferably the valve plate 93 will be engaged with the end 92 of the by-pass tube 91 with a slight initial pressure due to the inherent resiliency of the diaphragm so that the by-pass tube will be closed when the pressure in the side 83 of the valve chamber is slightly below the pressure in the refrigeration system to be sure that atmospheric air does not enter the system.

It will now be observed from the foregoing specification that the present invention provides a check valve of novel construction arranged between the absorber and vacuum pump which operates automatically to permit non-condensable gases to be withdrawn from the system while preventing the flow of atmospheric air into the system. It will also be observed that the valve of the present invention is automatically operable by the difference in pressure occurring at opposite sides of the valve.

While a preferred embodiment of the invention is herein shown and described as applied to an absorption refrigeration system, it will be apparent to those skilled in the art that the valve may be applied to other systems and may have other uses than that herein shown and described.

It will also be apparent that various modifications and changes may be made in the construction and arrangement of the parts of the valve without departing from the spirit and scope of the invention.

What is claimed is:

1. In an absorption refrigeration system having a plurality of elements interconnected to provide a closed circuit for the circulation of refrigerant and absorption solution, exhausting means, a conduit connecting the exhausting means to one of the elements of the system to withdraw non-condensable gases therefrom, valve means between the refrigeration system and exhausting means for opening and closing the conduit to the flow of non-condensable gases, and a flexible diaphragm for operating the valve means, said diaphragm having its opposite sides subjected to the pressures occurring at opposite sides of the valve whereby to close the valve when the pressure on the exhaust side thereof is the same or greater than the pressure in the refrigeration system and to open the valve when the pressure on the exhaust side thereof is less than the pressure in the refrigeration system.

2. In an absorption refrigeration system having a plurality of elements interconnected to provide a closed circuit for the circulation of refrigerant and absorption solution, exhausting means, a conduit connecting the exhausting means to one of the elements of the system to withdraw non-condensable gases therefrom, an automatically operable check valve in the conduit comprising a valve seat and a movable valve plate, a flexible diaphragm mounting the valve plate, and means for subjecting the opposite sides of the diaphragm to the pressure prevailing at opposite sides of the valve whereby to close the valve when the pressure on the exhaust side thereof is the same or greater than the pressure in the system and to open the valve when the pressure on the exhaust side thereof is less than the pressure in the system.

3. In an absorption refrigeration system having a plurality of elements interconnected to provide a closed circuit for the circulation of refrigerant and absorption solution, exhausting means, a conduit connecting the exhausting means to one of the elements of the system to withdraw non-condensable gases therefrom, said conduit comprising a chamber, a flexible impervious diaphragm extending across the chamber, and a by-pass connecting the chamber at opposite sides of the diaphragm, said diaphragm cooperating with the by-pass to close the latter when the pressure on the exhaust side of the diaphragm is the same or greater than the pressure in the refrigeration system.

4. In an absorption refrigeration system having a plurality of elements interconnected to provide a closed circuit for the circulation of refrigerant and absorption solution, exhausting means, a conduit including a chamber connecting the exhausting means to one of the elements of the system to withdraw non-condensable gases therefrom, a flexible impervious diaphragm extending across the chamber, and a by-pass connecting the chamber at opposite sides of the diaphragm, one end of the by-pass being so arranged as to be engaged by the diaphragm to prevent the flow of gases and to flex away from the end of the by-pass to permit the flow of gases therethrough.

5. In an absorption refrigeration system having a plurality of elements interconnected to provide a closed circuit for the circulation of refriger-

erant and absorption solution, exhausting means, a conduit connecting the exhausting means to one of the elements of the system to withdraw non-condensable gases therefrom comprising a chamber, a flexible impervious diaphragm extending across the chamber, conduit sections connecting the chamber at opposite sides of the diaphragm to the exhausting means and element respectively, and a by-pass tube having one end connected to the conduit section between the diaphragm and exhausting means and its opposite end extending into the conduit section between the diaphragm and element to provide a valve seat adjacent the diaphragm, said diaphragm being engageable with the valve seat at the end of the by-pass tube to close the latter and operable by the difference in pressure at opposite sides thereof to flex away from the end of the valve seat to open the by-pass.

6. In an absorption refrigeration system having a plurality of elements interconnected to provide a closed circuit for the circulation of refrigerant and absorption solution, exhausting means, a conduit connecting the exhausting means to one of the elements of the system to withdraw non-condensable gases therefrom comprising a chamber, a flexible impervious diaphragm extending across the chamber, conduit sections connecting the chamber at opposite sides of the diaphragm to the exhausting means and element respectively, and a by-pass having one end connected to the conduit section between the diaphragm and exhausting means and its opposite end extending into the conduit section between

the diaphragm and element of the system to provide a valve seat adjacent the diaphragm, and a valve plate mounted on said diaphragm, said diaphragm being operable by a difference in pressure at opposite sides thereof for engaging the valve plate with the valve seat to close the by-pass or flexing away from the end of the valve seat to open the by-pass.
